UNITED STATES PATENT OFFICE.

THOMAS A. FLANNIGAN, OF PHILADELPHIA, PENNSYLVANIA.

COMBINED SHOE AND LEGGING.

1,154,109.

Specification of Letters Patent. Patented Sept. 21, 1915.

Application filed May 24, 1915. Serial No. 29,953.

To all whom it may concern:

Be it known that I, THOMAS A. FLANNIGAN, a citizen of the United States, residing in the city and county of Philadelphia, State 5 of Pennsylvania, have invented a new and useful Combined Shoe and Legging, of which the following is a specification.

My invention comprehends a new and useful combined shoe and legging which is so 10 formed that it can be quickly and easily put on and removed, and which, while preserving the appearance of a legging and being a shoe, overcomes the objectionable feature of the necessity of lacing the shoe.

15 It further comprehends a shoe and legging so combined that relative movements of both the front portion of the legging and the shoe are permitted.

It further comprehends other novel features of construction, all as will be herein- 20 after fully set forth.

For the purpose of illustrating my invention, I have shown in the accompanying drawing certain types and embodiments of 25 it which, at present, are preferred by me, because in practice, they have given satisfactory and reliable results.

Figure 1 is a perspective view of a combined shoe and legging embodying my invention. Fig. 2 is a side elevation partly 30 sectional, and Fig. 3 is a perspective view, sectional on line $x-x$ Fig. 1, with the parts in open position, both of the construction represented in Fig. 1. Fig. 4 is a perspective view of another form of my invention 35 with the legging in open position and showing its connections between the tongue and the sides of the legging. Fig. 5 is a sectional view on line $y-y$ Fig. 4, with the parts in 40 closed position.

Similar numerals of reference indicate corresponding parts in the figures.

Referring to the drawings:—1 designates the vamp of a shoe, extending upwardly 45 from the inner portions of which is a tongue 2. The tongue and vamp are formed in one piece and the vamp extends from side to side of the shoe without any opening, so that the necessity of any fastening means is obviated.

50 3 designates a back foxing which is suitably connected at its forward side edges with the rear side edges of the vamp 1, as by stitching 4, it being noted that the stitching or connection between the vamp and back foxing terminates at a point adjacent the tongue 2, as at 5,

6 designates an opposite and counterpart back foxing which is connected to the vamp, in a manner similar to that already described with respect to the back foxing 3. 60

It will be understood that the sole, the heel, and the other ordinary parts of the shoe, may be formed and connected in any desired manner.

Both of the back foxings have extensions 65 which reach upwardly a suitable distance to form the opposite sides 7 and 8 of the legging, and the rear edges of the back foxings 3 and 6 and of the extensions 7 and 8 may be connected in any suitable or desired manner. 70 I have shown them as provided with the back stay 9 which is secured to the back foxings and also to the extensions 7 and 8 to provide a suitable finish to the connection between them. 75

10 designates a flap carried by one of the extensions, as for example, the extension or side 8, which flap extends outwardly from said side 8 at a point spaced from the termination 5 of the connection with the vamp 80 1, is adapted to be extended around the front of the leg and to overlap the other side member 7 passing over the tongue 2, as will be understood from Figs. 1 and 2, and is further adapted to be secured in any desired manner to the overlapped extension 7. 85

As here shown, I have provided straps 11 and buckles 12 common to the flap and overlap extension 7, which serve as a means for detachably connecting the parts when in 90 position.

I provide a U-shaped recess or notch 13 at the lower extremity of the point of extension of the flap from the side 8 of the legging, in which the tongue 2 is seated and 95 by means of which movement between the parts over the instep is provided, with the result that rubbing and injury to the instep of the wearer are prevented.

It will be understood that the shoe and 100 legging are preferably formed of leather, and for the reason that the lower edge of that portion which extends around the front of the leg terminates at a point above the natural break of the foot at the top of the 105 instep, and by reason of the fact that the seams connecting the back foxings with the vamp each lie in an approximately vertical plane passing through said point, I am enabled to provide great flexibility at the 110 instep, with its evident resultant advantages, and also permit a tight engagement

of the parts around the ankle to suitably support it.

In some instances, it may be of advantage to close the space between the tongue and the inner walls of the sides 7 and 8 of the legging to prevent water or moisture from reaching the interior, and in Fig. 4, I have shown a bellows-like connection between the tongue 2 and the sides 7 and 8 which I form 10 by the angularly extending wings or folds 14 and 15 which project from the tongue 2 and are connected, as at 16, with the sides 7 and 8 of the legging. By reason of the above construction, it will be seen that by disengaging the fastening means between the flap 10 and side 7, the legging may be thrown 15 open into the position seen in Fig. 4 for ease of putting on or removing the shoe, the connection between the sides of the legging 20 serving to hold them in close relation to the leg of the wearer, as well as to obviate the necessity of having any fastening or engaging means for the shoe.

It will now be apparent that I have devised 25 a novel and useful combined shoe and legging, which embodies the features of advantage enumerated as desirable in the statement of the invention and the above description, and while I have, in the present 30 instance, shown and described a preferred embodiment thereof which will give in prac-

tice satisfactory and reliable results, it is to be understood that the same is susceptible of modification in various particulars without departing from the spirit or scope of the 35 invention or sacrificing any of its advantages.

Having thus described my invention, what I claim as new and desire to secure by Letters Patent, is:—

A combined shoe and legging, comprising a vamp and a tongue extending upwardly therefrom, back foxings connected with the vamp along their front edges and having extensions to form the sides of the legging, 45 with their rear edges connected, a flap carried by one of the sides of the legging to overlap the other side with the lower edge of that portion which extends around the front of the leg terminating at a point above 50 the natural break of the foot at the top of the instep, and means for connecting the flap with the overlapped side, the seams connecting the back foxings with the vamp each lying in an approximately vertical plane 55 passing through said point, to provide flexibility at the instep and permit a tight engagement around the ankle.

THOMAS A. FLANNIGAN.
